CASSEROLE OR SIMILAR ARTICLE

William M. Curtis, Painted Post, N.Y., assignor to Corning Glass Works, Corning, N.Y., a corporation of New York

Filed Sept. 7, 1961, Ser. No. 66,636

Term of patent 14 years

(Cl. D44—15)

FIG. 1 is a top plan view of a casserole or similar article embodying my new design.

FIG. 2 is a partial side elevational and partial vertical sectional view of the same.

FIG. 3 is a sectional elevation of a fragment of the casserole, on an enlarged scale, taken on line 3-3 of FIG. 1.

The design is characterized by an outwardly directed rim which is of substantially greater width at the ends than along the sides and has a downwardly depending skirt at its outer edge, the upper surface of said rim at the ends of said article and in regions intermediate the middle and ends of said article sloping upwardly in the direction of the outer edge of said rim.

I claim:

The ornamental design for a casserole or similar article, as shown and described.
